UNITED STATES PATENT OFFICE.

RICHARD H. MORROW AND JAMES MORROW, OF WAUKEGAN, ILLINOIS.

ELECTRIC VACUUM-CLEANER.

1,142,353.

Specification of Letters Patent.

Patented June 8, 1915.

Application filed February 10, 1912. Serial No. 676,899.

To all whom it may concern:

Be it known that we, RICHARD H. MORROW and JAMES MORROW, citizens of the United States, and residents of Waukegan, in the county of Lake and State of Illinois, have invented certain new and useful Improvements in Electric Vacuum-Cleaners, of which the following is a specification.

This invention relates to a power cleaner 10 of the class described, which utilizes an electric motor for the motive power, and one of the principal objects of the invention is to provide an improved, compact and simple device of this class which is efficient in operation.

15 A further object of the invention is to provide a machine of the class described in which pressure may be applied directly to the inlet nozzle or opening.

20 Another object of the invention is to provide means whereby the machine may be pushed under an article of furniture or similar articles, and will lie flat on the floor in such a position so that pressure may be applied adjacent the inlet nozzle.

25 Another object of the invention is to provide a casting for the fan and the inlet nozzle of improved construction and formation.

Another object of the invention is to provide 30 a motor casing to which the fan case may be directly secured.

For the attainment of these ends and the accomplishment of other new and useful objects, as will appear, this invention consists 35 in the features of novelty in the construction, combination and arrangement of the several parts generally shown in the accompanying drawings and described in the specification, but more particularly pointed 40 out in the appended claims.

In the drawings Figure 1 is a view in side elevation of a machine constructed in accordance with the principles of our invention; Fig. 2 is a view in front elevation 45 of the same, part of the handle member being omitted; Fig. 3 is a view of the detailed construction of the motor and motor casing; Fig. 4 is a view in longitudinal cross section of a cleaner of this kind; Fig. 5 is a plan view taken on line 5—5 of Fig. 4; Fig. 6 is 50 a detail view of an attachment which may be positioned adjacent the axial opening of the fan casing; Fig. 7 is a plan view of the exterior opening in the inlet chamber which 55 registers with the opening in the fan chamber.

In machines of the class to which the present invention belongs, it is desirable that means be provided to enable the operator to push the machine under an article 60 of furniture, such, for example, as a chair or a bed, without danger of upsetting the machine or of tilting the inlet end upward, so that it cannot accomplish its desired result. It is also desirable that means be provided for exerting a pressure upon the inlet nozzle or adjacent the inlet nozzle, so that any particles of dirt which adhere particularly to the surface to be cleaned, may be subjected to additional pressure or scraping 70 by exerting a downward pressure upon the handle. If the handle is attached intermediate of the body of the machine it requires a greater pressure to exert the desired downward pressure at the inlet nozzle and unless 75 the point of support of the handle member is sufficiently low with respect to the machine, is more subject to a tipping action when moved across the surface to be cleaned. By mounting the handle member at a low 80 point at the forward end of the machine, this difficulty is avoided and the pressure applied to the handle is directed almost entirely to the nozzle member at the exact point where the pressure is desired. In ad- 85 dition, the applicants' construction is productive of other new and useful results which will be hereinafter set forth.

Referring now more particularly to the drawings and in the present exemplification 90 of our invention, the numeral 12 designates generally a motor of any desired or suitable form, but in the present instance a particularly designed alternating current motor of the series type, which is capable of a great 95 many revolutions a minute. In this motor the pole pieces 13 are provided with windings 14, and inclosing them at one end is a casing 15 which provides a bearing support for an armature shaft 16. This casing is 100 provided with projections 17 at the side adjacent the bearing support against which the pole pieces 13 abut and into these projections a rod 18 which also passes through the pole pieces, is threaded and provided 105 with a nut 19 which is adapted to be moved against the pole pieces to hold them in position with respect to the casing 15. This casing is also provided with an opening 20 through which the conductors for conveying 110 the electric current to the motor may be inserted, and adjacent the bearing may be

provided with an oil cup 21 of any suitable design or structure.

A casing member 22 having an extending lip portion 23 which is adapted to be inserted within the casing 15 at the opposite end of the motor is provided with a suitable flat end or face portion 24, which forms a bearing for the armature shaft 16 at the other end of the motor. This bearing is 10 also provided with an oil cup 25 which extends through the casing member 22 and which may be moved or adjusted from the outside thereof.

The motor shaft 16 preferably extends beyond the face 24 of the casing member 22 and mounted thereon in any suitable manner is a fan 26. Surrounding the fan 26 and secured to the adjacent motor casing 22 is a fan case 27. This fan case comprises a 20 fan chamber 28 substantially circular in form in which the fan 26 rotates, and is provided with a discharge outlet opening in the periphery thereof in the form of a bent tube or extension 29. Formed integral 25 with the fan case and substantially parallel with it is an inlet casing 30 which incloses an inlet chamber 31, the outer wall of the fan chamber and the inner wall of the inlet chamber being common. To afford communication between the inlet chamber 31 and the fan chamber 28 an opening 32, preferably circular in form, is provided, preferably disposed adjacent the axis of the motor and the center of the fan. In the 35 outer wall of the inlet chamber 31, and preferably registering with the opening 32 between the fan and inlet chamber is an opening 34, and in this opening there is disposed a plug or closure 35. This plug 35 may be 40 held in the opening in any desired manner, such, for example, as by means of the projections 36, which may be moved into the opening 34 (see Fig. 7) through the slots 37 and the plug then rotated to engage the 45 lips of the opening, whereby it will be held firmly in position.

The inlet chamber 31 is preferably of a form diverging from the central opening 32, and extending downwardly in a substantially inverted V or wedge shaped form, so that the lower edge extends below the fan casing and laterally beyond the sides thereof. The lower face of the inlet casing 30 is formed with a slot or inlet opening 38, which may be provided with cross bars 39 to prevent the ingress of large particles of dirt or foreign material which would tend to clog the fan, and the lateral edges or lips 40 surrounding the opening 38 are preferably 55 rounded so that they will not tend to scratch or mar the surface over which the cleaner is moved.

Formed integral with the fan casing and preferably adjacent the lip or lower edge 60 of the inlet casing are lugs 41 with openings

therein which extend preferably in opposite direction. These lugs 41 are adapted to seat the ends of a handle 42, which is provided with the extremities 43 extending around the motor casing and pivotally movable in the said lugs. 70

It will be evident that the fan casing and the depending inlet chamber extend beyond the casing of the motor 12, so that it is necessary to provide means for supporting the 75 end of the machine adjacent the motor. For this purpose a shaft 44 is secured beneath the motor casing 15 upon which are mounted the wheels 45. These wheels are preferably 80 provided with tires 46 of any desired or suitable material, such as rubber and the like, and the lower faces of the wheels are substantially in the same plane as the face of the opening 38 in the inlet casing 30. The shaft 44 preferably projects at both ends 85 beyond the wheels 45 and a cotter pin 47 may be provided to hold the wheels in position, the projecting portion of the shaft 44 being for the purpose of engaging the extremities 43 of the handle member 42. It 90 will be evident that the points of pivotal support of the handle, viz., lugs 41, are located below the shaft 44, so that it is necessary to provide the members 43 each with a bent portion 48, in order that the other 95 end of the handle 42 may strike the surface upon which the cleaner is supported without tilting the forward end of the machine upwardly. This will be evident from an inspection of the dotted portion of the handle 100 42, as shown in Fig. 1, and it will be seen that in this position the outer end of the handle may strike the surface upon which the cleaner is supported without raising the forward end of the cleaner or without pressing materially upon the shaft 44. If there is a tendency of the rear end of the cleaner to tip upwardly, the shaft 44 will engage the extremities 43 and will prevent the cleaner from tipping upwardly. From this 105 description it will be evident that any pressure which is exerted upon the handle is communicated directly to the inlet end of the cleaner, and when it is desired to exert a greater pressure at the inlet, for example, 110 when it is desired to remove or loosen dirt which adheres closely to the surface to be cleaned, it is necessary only to press downwardly upon the handle member and to move the inlet nozzle across the surface to 115 be cleaned. 120

Secured to the outlet tube 29 in any desired or suitable manner is a bag or receptacle 49, which is substantially impervious to dust and dirt. This bag 49 is supported at the end remote from the tube 29 upon the handle 42 by means of the hooks 50, and any desired or suitable fastening device in connection with the bag. It will be evident that when the handle 42 is in the full line posi- 125 130

tion shown by Fig. 1, the distance of one of the hooks 50 from the other end of the bag is less than when the handle is in a lower position, for example, as that shown in the dotted outline, and in the latter case it is necessary to support the bag 49 from a hook 50 at a less distance from the point of pivotal support of the handle.

In operation it is necessary only to start the motor and to move the inlet nozzle or opening 38 over the surface to be cleaned, whereupon the suction produced by the fan 26 will cause the air and particles of dust and dirt to be drawn up through the inlet opening 38 through the inlet chamber 31, and through the axial opening 32. The fan may be described as of a centrifugal type in which the air and dust is admitted adjacent the axis of the fan and is thrown off from the periphery thereof, the mixture of dirt and air being forced into the bag 49 which is impervious to the passage of the dirt, but permits the escape of air therefrom in the well known manner.

If desired a cleaning attachment as shown in Fig. 6 may be provided, which consists of a cleaning hose 51, having a coupling 52, adapted to be inserted through the opening 34 in the inlet casing 30, and through the opening 32 between the fan chamber 28 and the inlet chamber 31. This effectively closes the inlet chamber 31 from communication with the fan chamber 28, and causes the fan to draw air through the tube or hose 51. If desired the coupling or connection 52 may be provided with lugs 53 which are inserted through the slots 37 in the sides of the opening 34 (see also Fig. 7), and engaged by rotating the coupling 52.

In the preferred construction the current for the motor is connected thereto by means of a conductor 54, which is seated in a groove 55 in the handle 42, and is preferably provided at the upper end of the handle 45 with any desired or suitable connecting members or plug connections therefor.

The motor casing at the end adjacent the fan is of a particular construction, so that the fan casing may be secured directly thereto, thereby resulting in a compact, simple arrangement in structure which occupies little space.

It will also be evident that this cleaner may be used for removing dirt and the like from beneath articles of furniture or similar inaccessible places, and that while in such position the cleaner will be held in the correct position for removing the material, and also in such a position that pressure may be applied to the nozzle portion of the cleaner.

It will be evident that if there is a tendency for the cleaner to tip backwardly, the forward extremities 43 will strike the fan casing 27, and will prevent the cleaner from being overturned in this direction. With

this construction and arrangement the tendency to tip in either direction is minimized, and the nozzle of the cleaner is maintained in the proper position under all circumstances. Pressure may be applied directly to the nozzle and if it is desired to lift either end of the cleaner it may be accomplished with little effort for the reason that the pivotal connection of the handle member is at the front of the cleaner and this end 70 may be easily raised, and by rotating the handle until the extremities strike the fan case, the motor end may be easily raised because of the leverage which is obtained by the handle.

What is claimed as new is:—

1. The combination with a motor comprising a shaft, a casing which forms bearings for the motor shaft, a fan mounted on the shaft outside of the motor casing, a fan 85 casing removably secured to the motor casing and provided with a peripheral outlet opening, and an integral inlet chamber of which the fan casing forms one of the walls communicating with the fan chamber adjacent 90 the axis of the fan and extending below and laterally of the fan chamber, the lower edge of the inlet chamber being provided with an inlet slot.

2. In a vacuum cleaner, the combination 95 with a motor having a casing, of a fan casing secured to the casing at the front end of the motor and having a depending inlet portion, a shaft mounted below the motor at the other end, wheels mounted on the shaft, 100 the ends of the shaft projecting beyond the wheels, and a handle member pivotally mounted in the said depending portion and adapted to engage the said projecting ends 105 of the shaft when the rear end of the cleaner is upturned.

3. In a vacuum cleaner, the combination with a motor casing, of a fan case secured to the casing at one end, having a depending inlet portion, a shaft mounted below the 110 motor, wheels mounted thereon and providing bearing members for the adjacent end, the ends of the shaft projecting beyond the wheels, and a handle pivotally mounted in the said depending portion and adapted to 115 engage the said projecting ends of the shafts, or the fan case, to limit the movement of the cleaner with respect to the handle when it tends to upset in either direction.

4. In a vacuum cleaner, the combination 120 with a motor casing, of a fan case secured to the casing at one end, having a depending inlet portion, a shaft mounted below the motor at the other end, wheels mounted thereon and providing bearing members for the adjacent end of the cleaner, the ends of the shaft projecting beyond the wheels, and a handle having a forked end portion pivot- 125 ed in the depending portion and adapted to engage the projecting ends of the shaft. 130

5. In a vacuum cleaner, the combination with a motor casing, of a fan case secured to the casing at one end, having a depending inlet portion, a shaft mounted below the motor, wheels mounted thereon and providing bearing members for the adjacent end, the ends of the shaft projecting beyond the wheels, and a handle having a forked end portion pivoted in the depending portion and adapted to engage the projecting ends of the shaft, the forked end portion being offset to permit the handle to extend adjacent a plane surface when the cleaner is disposed thereon.
- 10 15. 6. In a vacuum cleaner, the combination with a motor casing, of a fan case and an integral depending inlet portion removably secured to the motor casing, a shaft mounted below the motor, wheels mounted thereon, and a handle provided with a forked end pivotally mounted in the depending portion below the said shaft, the forked end being offset between the points of pivotal support and the ends of the shaft to allow the

handle to rest on the surface on which the 25 cleaner is supported.

7. In a vacuum cleaner, the combination with a motor casing, of a fan case and an integral depending inlet portion removably secured to the motor casing, a handle provided with a forked end pivotally mounted in the depending portion, and means in connection with the motor casing to engage the forked portion of the handle, the handle being provided with an offset portion to permit it to rest on the floor, and to engage the said means when the cleaner is turned upwardly.

In testimony whereof we have signed our names to this specification, in the presence of 40 two subscribing witnesses, on this 7th day of February A. D. 1912.
